UNITED STATES PATENT OFFICE.

JACOB SILVERBERG, OF PITTSBURG, PENNSYLVANIA.

SIPHON.

No. 895,694.

Specification of Letters Patent.

Patented Aug. 11, 1908.

Application filed January 6, 1905. Serial No. 239,849.

To all whom it may concern:

Be it known that I, JACOB SILVERBERG, a resident of Pittsburg, in the county of Allegheny and State of Pennsylvania, have invented a new and useful Improvement in Siphons; and I do hereby declare the following to be a full, clear, and exact description thereof.

My invention relates to siphons, and has special reference to the ordinary form of portable siphons for emptying the contents of barrels, casks, etc.

The object of my invention is to provide a cheap and simple form of siphon whereby the contents of a barrel or cask may be easily and quickly removed therefrom intermittently or continuously, as desired, in the filling of bottles, jars, &c., or for other purpose.

I will now describe my invention, referring to the accompanying drawing, in which,

Figure 1 shows a cross-section of a barrel having my improved siphon applied thereto and in position for operating in filling a bottle. Fig. 2 is an enlarged side view of the receiving end with the lower portion in section. Fig. 3 is a like view of the adjusting sleeve for the siphon tube. Fig. 4 is a top plan view of the same, partly in section. Fig. 5 is a longitudinal section of the exhaust cylinder with its operating parts connected thereto. Figs. 6 and 7 are views showing different connections for filling different sizes of vessels. Fig. 8 is a view of a nipple for use in filling different sized necks of vessels.

Like symbols of reference indicate like parts in each figure.

In the drawing, 1 represents the ordinary flexible siphon-tube, the usual short leg 1' of which is adapted to be passed through the bung - hole of the barrel A and carries a strainer-sinker 2 which is provided with a notched nipple 2' at its upper end for connecting it to said leg 1'. The strainer-sinker 2 is exteriorly of a size to permit its passage through the bung-hole a and is provided with a threaded annular flange 2'' at its lower end with which a threaded annular flange 3'' on a sleeve 3 is adapted to engage for confining a strainer 4 and washer 5. Extending from the sleeve 3 is a series of projections or lugs 6 affording passageways between them for use when the sinker is resting on the bottom of the barrel. The siphon-tube 1 is also provided with the usual long leg or delivery portion 1'', while between the legs 1' and 1'' is an adjusting sleeve 7, which fits around the

tube 1 and is formed of a curved portion 7' and a straight portion 7''. The curved portion 7' carries at its end the leg 1' and extends through the bung-hole of the barrel, while thumb-screws 8 engage by their threaded ends 8' with threaded bushings 8'' on each side of the sleeve 7, the thumb-screws resting against the exterior surface of the barrel.

At the delivery end of the siphon tube 1, 65 is the exhaust cylinder 10, which is connected to the tube by means of an elbow 11 brazed to a boss 11' on one side of the cylinder. A stop-cock 12 having a valve 12' is brazed to the opposite side of the cylinder, 70 and the openings 13 and 13' leading into the boss 11 and cock 12 are in the shape of perforations to form strainers. The piston 14 of the cylinder 10 is preferably formed of leather and is connected to a piston-rod 15 75 provided with an operating handle 14' at its outer end.

The operation of my improved siphon is as follows:—When it is desired to fill a vessel, such as the bottle B, the adjusting sleeve 7 is 80 moved along the siphon tube 1 to such position that the sinker 2, when the leg 1' is passed into the barrel, will be but slightly below the level of the liquid in the barrel, the clamping screws 8 preventing it from falling below such position. The bottle B is then placed in position and the operator pulls the piston 14 outwardly by the handle 14', which exhausts the air from the siphon tube, and the contents of the barrel will then 85 flow into the bottle. When the bottle has been filled, another bottle is placed in position, and filled, and this operation may be repeated as long as desired or until the barrel has been emptied. As the contents of the 90 barrel are gradually lowered, the sinker can be kept always sufficiently immersed therein by simply sliding the adjusting sleeve back along the tube 1 the desired distance so as to lengthen the leg 1'. 100

In case it is desired to fill two bottles at one time, all that is necessary is to screw the plug 16, shown in Figs. 6 and 7, on to the threaded end 12'' of the cock 12, and then, by screwing interchangeable and different 105 sized branch pipes 16' into said plug, different sizes of bottles can be filled at one time, while it will also be evident that for filling narrow neck bottles, a notched screw plug 17, such as shown in Fig. 8, can be screwed 110 on to the end 12''.

It will also be evident that the thumb-

screws 8 may be screwed up so that the ends thereof will slightly engage the siphon tube 1 in order to hold said tube against any tendency to slide in said sleeve.

5. I claim:—

In a siphon, a cylinder having at one side and near one end a strainer connecting it to the long leg of the siphon, and at the opposite side and near the same end a second strainer, a delivery faucet connected to said

cylinder by said second strainer, and a solid piston in said cylinder for starting the siphon in operation, substantially as described.

In testimony whereof, I the said JACOB SILVERBERG have hereunto set my hand.

JACOB SILVERBERG.
